UNITED STATES PATENT OFFICE.

HUGH W. BATCHELLER, OF BETHEL, VERMONT, ASSIGNOR TO BOJAC MANUFACTURING CO., INC., OF BURLINGTON, VERMONT, A CORPORATION OF VERMONT.

ELECTRICAL CONNECTER.

Application filed August 1, 1924. Serial No. 729,489.

This invention relates to an electrical connector comprising a socket, such as that commonly used to support an incandescent electric lamp, the socket being provided with 5 internal conducting members adapted to connect the lamp, which is located at one end of the socket, with a conducting cable at the opposite end of the socket.

The object of the invention is to provide 10 an improved construction of the socket, the internal conducting members, and the means securing the internal members to the socket, whereby a simple, durable and relatively inexpensive connector is produced, the parts 15 of which are adapted to be quickly and securely assembled.

Of the accompanying drawings forming a part of this specification,—

Figure 1 shows partly in elevation and 20 partly in section, an electrical connector embodying one form of the invention.

Figure 2 shows in elevation, the connector shown by Figure 1 engaged at one end with a plug, and at the opposite end with the shell 25 of a lamp bulb.

Figure 3 is a view similar to Figure 1 showing two sets of internal conducting members.

Figure 4 is a fragmentary view similar to 30 a portion of Figure 1 illustrating the operation of assembling the parts.

Figure 5 is a section on line 5—5 of Figure 2.

Figure 6 shows partly in section and partly in elevation a different embodiment of the 35 invention.

Figure 7 is a view similar to Figure 6 illustrating a part of the operation of assembling the parts.

40 The same reference characters indicate the same parts in all of the figures.

Referring first to Figures 1 to 5, 12 designates a tubular socket of any suitable metal from which opposed stops may be formed.

45 To provide said stops I form two series of tongues 13 integral with the tube by partly severing portions of the tube wall and bending said portions inward after the insertion of the holders or washers hereinafter described, so that each tongue has a side face normally inclined inward from the wall, and an end face at an angle with the side face,

50 each series of tongues collectively constituting a stop. 14, 14 designate two independent holding members or washers of insulat-

ing material movable longitudinally into the socket and located side by side therein, said washers being preferably discoidal and formed to somewhat closely fit the inner wall of the socket. The washers are provided with orifices 15 adapted to receive tubular portions or sections 16 of telescopic conducting members, which are adapted to conduct current from a contact member 17 at one end of a flexible conductor 18 secured to a plug 20 at one end portion of the socket, to a contact member 19 at the inner end of the shell 20^a of an electric lamp. The sections 16 are provided with flanges 21 seated on the adjacent side faces of the washers 14. The washers 14 and the conducting members engaged therewith constitute an internal structure composed of parts adapted to be assembled in the socket, as next described. In assembling the described parts, the conducting member sections are slipped into the washer orifices 15, and the washers are forced into the socket until they are between the tongues, the latter being flush with the tube wall as shown by full lines in Figure 4, and the flanges 21 being abutted against each other. The tongues are then bent or swaged inward as shown by full lines in Figure 1 and by dotted lines in Figure 4, to form stops confining the washers as shown by Figure 1. 85 The parts are so proportioned that when the washers are confined by the end faces of the tongues, the flanges 21 of the conducting member sections are in close contact with each other, the stops immovably confining 90 the washers, and the washers bearing on the flanges 21 and abutting said flanges together.

Each conducting member preferably includes a tubular section 16 which I call a base section, a terminal section 23 which is movable in the base section, and a spring 24 adapted to press the two terminal sections outward and cause them to bear yieldingly on the terminals 17 and 19.

It will now be seen that the described parts 100 may be quickly, conveniently and inseparably assembled by first inserting the conducting members in the washers 14, then forcing the washers into the socket, and finally confining the holders by converting the tongues into stops seated on the outer faces of the washers.

The connector may be of the single contact type shown by Figures 1, 2 and 5, or the double contact type shown by Figure 3, 110

these differing only in the number of internal conducting members and contacts employed.

Figures 6 and 7 show a connector of the single contact type, the construction of which differs from that shown by Figures 1 and 2 in that there is only one series of tongues 13, these forming an inner or secondary stop, the socket here designated by 12^a being provided with a primary stop 13^a substituted for the other series of tongues, and formed as an inwardly projecting shoulder on which one of the washers 14 is seated. In this modification, the parts are assembled by first inserting one washer 14 and its conducting member in the socket until the washer is seated on the primary stop 13^a, then inserting the other washer and its conducting member until the flanges 21 of the conducting members are abutted together, and then forcing inward the tongues 13 and thus forming a secondary stop which is seated on the washer last inserted and confines the structure formed by the washers and the conducting members.

It is obvious that the parts shown by Figures 1 to 5 inclusive, may be assembled in the same way that the parts shown by Figures 6 and 7 are assembled, that is to say, the lower tongues 13 may be forced inward to form a primary stop before the insertion of the washers and conducting members, said washers and conducting members being then inserted successively and confined by forcing the upper tongues inward to form a secondary stop.

In this modification, I show one telescopic conducting member constructed as above described, and a non-telescopic conducting member 26 to which the conductor 18 may be connected by a binding screw 27 or otherwise, the spring 24^a of the telescopic member being seated on the member 26. It is obvious that for some uses each of the two aligned internal conducting members may be of rigid, instead of telescopic construction, no springs being employed.

It will be seen that the inwardly projecting oppositely facing primary and secondary stops are spaced apart a predetermined distance which is equal to the collective thickness of the washers and the flanges of the conducting members, and that the two washers, when confined by the stops, are

spaced apart sufficiently to receive between their adjacent faces the flanges formed on the meeting ends of the conducting members, and hold said meeting ends in close contact with each other when the secondary stop is formed. The washers may, therefore, be economically punched from sheet material of suitable thickness, no recesses being required in the sides of the washers. The parts may be quickly and conveniently assembled, and confined by first inserting one washer and the corresponding conducting member in the socket to an extent permitted by the primary stop, then inserting the other washer and conducting member to an extent permitted by the meeting ends of the conducting members, and finally forming the secondary stop, and thereby confining the washers and clamping together the flanged meeting ends of the conducting members.

I claim:

1. An electrical conductor comprising a tubular socket having inwardly projecting primary and secondary stops spaced apart longitudinally of the socket a predetermined distance, two independent insulating washers whose collective thickness is less than the width of the space between said stops, and two aligned conducting members extending through the orifices in said washers and having their meeting ends provided with annular flanges which contact with the adjacent faces of the washers and maintain the latter in contact with the said primary and secondary stops.

2. An electrical conductor comprising a tubular socket having an inwardly extending annular, primary stop and a plurality of inwardly projecting secondary stops spaced longitudinally of the socket from said primary stop, two independent insulating washers whose collective thickness is less than the width of the space between the primary and secondary stops, and two aligned conducting members extending through the orifices in said washers and having their meeting ends provided with annular flanges which contact with the adjacent faces of the washers and maintain the latter in contact with the said primary and secondary stops.

In testimony whereof I have affixed my signature.

HUGH W. BATCHELLER.
